JOHN R. RICHARDSON, OF MAX MEADOWS, VIRGINIA.

Letters Patent No. 105,598, dated July 19, 1870.

IMPROVEMENT IN LOCOMOTIVE WHEELS.

The Schedule referred to in these Letters Patent and making part of the same.

To all whom it may concern:

Be it known that I, JOHN R. RICHARDSON, of Max Meadows, in the county of Wythe and State of Virginia, have invented a new and improved Device for Preventing Locomotive Wheels from Slipping on Railways; and I do hereby declare that the following is a full, clear, and exact description of the same, reference being had to the accompanying drawing forming a part of this specification, in which the figure is a side elevation.

This invention consists in the combination with the driving-wheel of a locomotive of an outside row of pivoted spurs, projecting beyond the periphery of the wheel, and engaging with the teeth of auxiliary rails, which are laid down outside the main rails, thus rendering it impossible for the wheels to slip on the track, the said spurs being combined with spring arms, which press against them with force sufficient to keep the spurs up to their work, and yet not too great to prevent them from yielding before an immovable obstacle, so as to avoid shocks; and with pins, which hold the spurs in their proper position against the pressure of the springs.

In the drawing—

A is one of the locomotive wheels.
a, the track on which it runs.

b, the projecting spurs, arranged in an annular row on the outside of the wheel.

c, the pins, against which the spurs bear.

d, the springs which press the spurs against the pins.

e, the teeth of the auxiliary outside rail.

By this arrangement any slipping of the wheels is rendered impossible, except in the very slight degree due to the yieldingness of the spurs, which yieldingness is a quality of the spurs necessary to guard against fracture.

Instead of the auxiliary toothed rails, I may use teeth furnished with shanks, the shanks being passed horizontally through the necks of the rails, and the teeth standing vertically outside the rails.

Having thus described my invention, What I claim as new, and desire to secure by Letters Patent, is—

In combination with a locomotive wheel, the spurs *b*, springs *d*, and pins *c*, all arranged and operating substantially as described.

JOHN R. RICHARDSON.
